UNITED STATES PATENT OFFICE.

EDWARD W. HART, OF OMAHA, NEBRASKA, ASSIGNOR TO MORRIS CASH AND CREDIT REGISTER COMPANY, OF OMAHA, NEBRASKA, A CORPORATION OF MAINE.

PAPER-FEED FOR MANIFOLDING-MACHINES.

1,363,508.

Specification of Letters Patent. Patented Dec. 28, 1920.

Application filed December 9, 1918. Serial No. 265,824.

To all whom it may concern:

Be it known that I, EDWARD W. HART, a citizen of the United States, and a resident of Omaha, in the county of Douglas and 5 State of Nebraska, have invented certain new and useful Improvements in Paper-Feed for Manifolding-Machines; and I do hereby declare that the following is a full, clear, and exact description thereof, reference being had to the accompanying drawings, and to the letters of reference marked thereon, which form a part of this application.

This invention relates to improvements in 15 paper feed for manifolding machines and is herein illustrated as applied to cash registers. The invention consists of the matters hereinafter referred to and more particularly pointed out in the appended claims. 20 The improved paper feed is shown herein as applied to cash registers of the kind described in the patent to J. L. Morris, No. 1,101,317 of June 28, 1914, and in the patent to J. L. Morris and A. W. Larimore, No. 25 1,292,354 of January 21, 1919, and, as illustrated herein, are shown in connection with such a cash register.

In a cash register of the kind described, there is provided in addition to the several 30 check strips for the usual "cash," "charge," "received on account," and "paid out" transactions, a record strip or strips for recording such transactions, said several check strips and the record strips being exposed 35 through suitable openings in the cover plate of the cash register, in order that the transactions may be written upon said strips.

In a cash register of the kind described, there is a master member or lever for feeding 40 the record strip or strips and for releasing the cash drawer locking mechanism,—said master member or lever being operable only after the record strip or strips are written upon through the opening or 45 openings through which they are exposed, and after a check has been issued.

The openings in the cover plate through which the check strips and the record strip or strips are exposed, are necessarily limited 50 by the width of the platen over which they pass, and this platen, in the case of the check strips, is only required to be of comparatively narrow width, and in many cases there is but the same required narrow width 55 for inscription upon the record strip or strips, namely, a sufficient width to write one

line. It sometimes occurs, however, in the entry of a transaction, that it may be desirable to use more than the space to be occupied by one line, in order to itemize an 60 entry on the record strip, as for example, when an amount of cash to be indicated on the check strip in the column "received on account" includes several different items, of no moment to be indicated on the check issued to the customer, but of necessity to be entered as a record of the proceeding upon the record strip. In such case it is desirable to be able to feed the record strip 65 one or more lines or spaces over the platen, 70 independently of the normal required feed of one space or line which is had in cash registers of the kind referred to, by means of the manipulation of the master member or lever, which finally feeds the check strip 75 and releases the cash drawer after the check has been issued to unlock said master member or lever.

The object of the present invention is to provide such an independent feeding mechanism for the record strip or strips and to provide it in such manner that while it may be operated independently of the master member or lever, its presence in the mechanism, in no way interferes with the control 80 heretofore had of the master lever, which operates in the same way and which has the same function as before, and in addition, the operation of said supplementary record feeding means is only possible in each case 85 in connection with a single total transaction written or inscribed upon one of the check strips.

In illustrating the invention, it is shown as applied to the construction of cash register 90 more particularly depicted in the Patent No. 1,292,354, above referred to.

In the drawings:

Fig. 1 represents a perspective view of a cash register in which my invention is embodied.

Fig. 2 represents a view in side elevation on an enlarged scale, of the actuating mechanism only of the cash register shown in Fig. 1.

Fig. 3 represents a vertical section through the cover plate of the cash register, and shows the relative location of several parts of register, more directly associated with said cover plate, the plane of the section 110 being indicated by the line 3-3 of Fig. 1.

Fig. 4 represents a top plan view of the

actuating mechanism of the cash register adjacent and below the right hand end of the cover plate which is indicated by dotted lines thereon.

5 Fig. 5 represents a detail vertical sectional view through parts shown in Fig. 4, the plane of the section being indicated by the line 5-5 of Fig. 4.

Fig. 6 represents another detail vertical 10 sectional view through parts shown, in Fig. 4, the plane of the section being indicated by the line 6-6 of Fig. 4.

Fig. 7 represents a top plan view of parts shown at the right hand end of Fig. 4, but 15 showing said parts in a changed position from that shown in said Fig. 4.

Fig. 8 represents a perspective view of a bar embodied in my invention and which will be more specifically referred to later.

20 Referring now in detail to that embodiment of the invention illustrated in the accompanying drawings:—10 indicates the box or cabinet which incloses the operating mechanism of a cash register of the kind described, to which the improvements referred to herein are applied. 11 indicates the cash drawer normally locked by mechanism which is only released upon the operation of the master member or lever; and 12 25 indicates the cover plate of the cash register. 13, 14, 15 and 16 indicate the openings in the cover plate which expose the several check strips above the platen; 13^a, 14^a, 15^a and 16^a, the normally locked slides by means 30 of which a preliminary feeding movement of the check strips may be brought about; 17 and 18, the openings through which the record strip is exposed; and 19 indicates the master member or lever which controls the 35 feed of the record strip and the unlocking of the cash drawer.

The construction and operation of the several parts referred to, except as herein-after pointed out, are the same as in the 40 patent and application heretofore mentioned, and require no further description, except to say that in illustrating this invention, but one record strip is used, instead of two as in the case of the application heretofore mentioned, said record strip 45 extending the width of the cover plate and being intended to be written upon in connection both with cash transactions as well as the other transactions, instead of there 50 being provided two independent record strips, one for cash and one for the other transactions, as in the case of the application mentioned.

55 20 indicates the record strip (see Fig. 3) 60 which is unwound from a supply roll 21 and after passing over the platen 22, is rewound upon a roll 23. The usual ink ribbons 24, one for each check strip, pass over the platen above the record strip,—25, 65 26 indicating respectively, the supply and

rewind rolls for said ribbons. 27 indicates one of the check strips (in this case, the one nearest to the opening 18, which exposes the record strip) which passes over the feed roll 28 and thence over the platen 22 above 70 the ink ribbon 24, under the inscription opening 16, and which is given its preliminary feed by the slide 16^a, when said slide is unlocked in a manner now well known.

The several slides for feeding the check 75 strips are released when a writing or inscription is made upon the record strip through the record strip opening 18, this being brought about as heretofore, by a depressible platen part indicated by 22^a (see 80 Fig. 4). Said depressible platen part 22^a is a spring controlled plate pivotally mounted on a pin 29 fixed to the main part of the platen. The right hand end of the platen part 22^a has a detent 30 which normally engages a horizontally swinging, spring controlled trigger 31, which acts to lock the several check strip feed slides, until the depressible platen part is written upon, when it acts to release said slides, and which is returned by the master lever to its normal locking position, as said lever is operated to feed the record strip and to release the cash drawer.

Passing now to the novel improvements 95 particularly intended to be covered herein:—32 indicates the upright end frame of the machine to the outside of which is pivoted the master member or lever 19. The same is pivoted on a screw 33 and its 100 shorter arm 34 is connected by a link 35 to a swinging arm 36, pivoted on a stud 37 and having a short finger 38. On the stud 37 is also pivoted, adjacent the swinging arm 36, an arm 39 carrying a pin 40, which 105 is engaged by the short finger 38 of the swinging arm 36. The arm 39 carries a pivoted pawl 41 adapted for engagement with a ratchet wheel 42 on the shaft 23^a of the record rewind roll 23. Said pawl is 110 provided with a slot 43 in which is engaged a pin 44 fixed to the end frame member 32. The pawl is spring controlled and the operation is such that when the master member or lever 19 is swung rearwardly (to the 115 left, as shown in Fig. 2), the swinging arm 36, by its engagement with the stud 40, will swing downwardly the arm 39 by which said stud is carried, and the pawl 41, by reason of its engagement with the stud 44, 120 and its pivotal connection with the arm 39, will be swung into engagement with the ratchet wheel 42 and will cause said ratchet wheel to turn through a certain angle which, as the machine is designed, is equal 125 to substantially the width of the platen. A spring controlled retaining pawl 45 pivoted on the stud 37 acts to hold the feed roll against back lash.

In addition to this master mechanism for 130

feeding the record roll, there is provided the following, supplementary, independent feeding mechanism. On the screw or stud 33, to which the master lever 19 is pivoted, 5 and adjacent thereto, there is pivoted a bell crank lever 46 having an upright arm 46^a and a horizontal arm 46^b. The arm 46^b is pivotally connected to the arm 39 on the same pivot by which said arm is connected 10 to the pawl 41, for operating the record re- wind roll. A slot 46^c is provided in the arm at this connection, to permit the nec- essary lost motion. The upright arm 46^a of said bell crank lever, is extended up- 15 wardly and rearwardly into a plane below the plane of the cover plate. Attached to the top of the end frame 32 in the plane of the cover plate, is a laterally extending plate 47 in which is formed a guide slot 48, 20 for the master lever. On the plate 47, is mounted a slide 49, said slide being sub- stantially of the same form as the slides used in connection with the feed of the check strips, and having an upright finger 25 49^a. The slide is attached to the plate by means of screws 50, 50, which take through a slot 51 in the plate 47 and are engaged in a bar 52 (see Figs. 6 and 8), which has its top surface engaged against the bottom side 30 of the plate 47. The construction is such that the screws 50, 50 guide the movement of the slide 49 in the slot 51, in a path parallel to the vertical plane of the end frame 32, and move the bar 52 on the under side of the plate 47 with the slide 49.

The bar 52 is cut as shown, to provide a lip 53 which is bent downwardly below the plane of said bar, to form a detent. Said detent depends into a position back of an 40 upright lug 31^a on the trigger 31, which is operable as heretofore described, by the depressible platen part 22^a. The construction is such that when the depressible platen part is operated by writing upon the record 45 strip, the trigger 31 swinging to the right (as viewed in Figs. 4 and 7), will remove the lug 31^a from the path of the detent 53. This unlocks the slide 49 so as to permit it to be moved forwardly on the plate 47.

50 The upwardly and rearwardly inclined part of the arm 46^a of the bell crank lever 46 is indicated by the numeral 46^d. This part 46^d of the arm 46^a is engaged at its rear end by a hook 54 on the bar 52,—said hook 55 being formed as shown, by bending down the rear end of said bar. An antifriction roller 46^e is preferably mounted at the rear end of the arm 46^a for immediate engage- 55 ment with the hook 54.

60 The operation of the supplementary feed- ing mechanism is as follows. The sup- plementary record feeding slide 49 in the be- ginning is locked by reason of the engage- 65 ment of the detent 53 on the bar 52 against the lug 31^a on the main trigger 31. When

the depressible platen part 22^a is depressed by reason of the writing or inscription made upon the record strip, the trigger 31, which is spring controlled, swings to remove the lug 31^a from the path of the detent 53,— 70 this occurring at the same time and in the same movement of the trigger in which the slides for partially feeding the check strips, are unlocked. This movement of the trig- 75 ger has no effect to unlock the master mem- ber or lever 19. But, the slide 49, being un- locked, may be pushed forwardly, that is to say, in the same direction as the check strip feeding slides are moved, and in this move- 80 ment there is caused a swinging movement of the bell crank lever 46,—this because of the engagement of the detent 53 on the bar 52 connected to the slide 49. The swinging movement of the lever 46 results in a move- 85 ment of the arm 46^b thereof to actuate the record strip feeding pawl 41,—(as shown in dotted lines in Fig. 2), this movement feed- 90 ing the record strip preferably the same distance that it would be fed if the master lever were released and capable of opera- 95 tion. This movement of the slide to feed the record strip may be repeated any num- ber of times to feed the record strip the necessary amount to write upon it through the opening 18, the number of different 100 items desired. In each case, after the for- ward movement of the slide 49, said slide and the bell crank lever 46 to which it is connected, are returned to their normal, ini- 105 tial positions, by reason of a spring 55, 100 which in this case is a coiled spring mount- ed on the screw 33, with oppositely acting arms 55^a, 55^b,—the one acting against the upright arm 46^a of the bell crank lever 46, and the other acting against the lever 19 in such manner as to normally hold each of 110 said levers in their initial positions and to return each of said levers to its initial posi- 115 tion when it has been removed therefrom.

It will be manifest from the description and illustration of the mechanism for pro- 120 ducing the independent feed of the record strip, that after the unlocking of the slide 49, brought about by the inscription through the opening 18, on the record strip, the feed of the record strip is entirely independent of the master lever. However, when the last independent feeding movement of the record strip has been produced, and the final feeding movement thereof, to present 125 a fresh space to correspond with the issue of the next check strip (this being coincident with the unlocking of the cash drawer), is to be made, as after the check strip has been pulled out and delivered, a last feed- 130 ing movement as always heretofore, is neces- sarily produced in the operation of the master lever. In this movement of the mas- ter lever, the trigger as heretofore, is swung back into the position to lock all the check

strip feed slides, and also in the same way, to lock the independent record strip feeding slide 49, which is locked by reason of the swinging back of the trigger to bring 5 the lug 31^a into the path of the detent 53 on the bar 52 connected to the slide 49.

While in describing the invention, there are referred to certain details of construction and of operation, it will be understood 10 that the invention is in no way limited thereto, except as pointed out in the appended claims.

I claim as my invention:

1. In a paper feed for manifolding machines of the kind described, in combination 15 with check strip feeding means, record strip feeding means, and a normally locked master member for operating said record strip feeding means, normally locked means for

20 independently feeding said record strip, a member for unlocking said independent record-strip-feeding means, and devices operated by said master member for relocking said independent record-strip-feeding means.

25 2. In a paper feed for manifolding machines of the kind described, in combination with check strip feeding means, record strip feeding means, and a normally locked master member for operating said record strip

30 feeding means, normally locked means for independently operating said record strip feeding means, a member for unlocking said independent record - strip - feed operating means, and devices operated by said master member for relocking said independent record-strip-feed operating means.

35 3. In a paper feed for manifolding machines of the kind described, in combination with check strip feeding means, a record strip feeding means, and a normally locked master member for operating said record strip

40 feeding means, normally locked means for independently feeding said record strip, means operable upon the writing on said record strip, for unlocking said independent record strip feeding means, and devices operated by said master member for relocking said independent record strip feeding means.

45 4. In a paper feed for manifolding machines of the kind described, in combination with check strip feeding means, a record strip feeding means, and a normally locked master member for operating said record strip feeding means, a platen including a compressible part over which said record strip is fed, normally locked means for independently feeding said record strip, means operated by said compressible platen part for unlocking said independent record strip feeding means, and means actuated by said master member for relocking said independent record strip feeding means.

5. In a paper feed for manifolding machines of the kind described, in combination 65 with check strip feeding means, a record

strip feeding means, and a normally locked master member for operating said record strip feeding means, means for independently feeding said record strip, a trigger normally locking said independent record strip feeding means, and means operable upon writing on said record strip for actuating said trigger to unlock said independent record strip feeding means, said trigger being actuated in the operation of 75 said master member to relock said independent record strip feeding means.

6. In a paper feed for manifolding machines of the kind described, in combination with check strip feeding means, a record 80 strip feeding means and a normally locked master member for operating said record strip feeding means, a platen including a compressible platen part over which said record strip is fed, means for independently 85 feeding said record strip, and a trigger normally locking said independent record strip feeding means, said trigger acting to unlock said independent record strip feeding means when said compressible platen part is depressed, and to relock said independent record strip feeding means when said master member is operated.

7. In a paper feed for manifolding machines of the kind described, including a 95 platen over which a record strip, transfer means, and a check strip are adapted to be fed, a cover plate provided with laterally spaced openings, one to expose the check strip and one to expose the record strip, 100 normally locked means for partially feeding said check strip, a normally locked master member for feeding said record strip, a normally locked slide bar for feeding said record strip independently of said master member, a spring controlled, compressible part included in said platen located below the opening which exposes said record strip, and means operated by said compressible platen part for unlocking said slide bar, said means 110 being actuated in the operation of said master member to relock said slide bar.

8. In a paper feed for manifolding machines of the kind described, including a platen over which a record strip, transfer means, and a check strip are adapted to be fed, a rewind roll for said record strip, a cover plate provided with laterally spaced openings, one to expose the check strip and one to expose the record strip, normally 115 locked means for partially feeding said check strip, a normally locked master member adapted for operative connection with said record rewind roll, a second lever adapted for operative connection with said rewind roll, a normally locked slide bar on said cover plate operatively connected to said second lever, a compressible part included in said platen located below the opening which exposes said record strip, and means oper- 120

125

130

ated by said depressible platen part for unlocking said slide bar without unlocking said master member.

9. In a paper feed for manifolding machines of the kind described, including a platen over which a record strip, transfer means, and a check strip are adapted to be fed, a rewind roll for said record strip, a cover plate provided with laterally spaced openings, one to expose the check strip and one to expose the record strip, normally locked means for partially feeding said check strip, a normally locked master member adapted for operative connection with said 10 rewind roll, a second lever adapted for operative connection with said rewind roll, a normally locked slide bar on said cover plate operatively connected to said second lever, a depressible part included in said platen 15 located below the opening which exposes said record strip, and means operated by said depressible platen part for unlocking said slide bar, said last mentioned means being actuated in the operation of said master member to relock said slide.

10. In a paper feed for manifolding machines of the kind described, including a platen over which a record strip, transfer means, and a check strip are adapted to be

fed, a rewind roll for said record strip, a cover plate provided with laterally spaced openings, one to expose the check strip and one to expose the record strip, normally locked means for partially feeding said check strip, a normally locked master member 35 adapted for operative connection with said rewind roll, a second lever also adapted for operative connection with said rewind roll, a normally locked slide bar on said cover plate operatively connected to said second 40 lever, a spring controlled, depressible part included in said platen, located below the opening which exposes said record strip, and a trigger engaged by said depressible platen part, normally holding said slide against 45 movement, said trigger when released by said platen part acting to unlock said slide bar and to again lock said slide bar when said master member is actuated.

In testimony that I claim the foregoing 50 as my invention, I affix my signature in the presence of two witnesses, this 5th day of December, A. D., 1918.

EDWARD W. HART.
